CLAIM

We claim the ornamental design for a toilet seat, as shown and described.

DESCRIPTION

FIG. 1 is a top front perspective view of a toilet seat and a pair of clamps in an extended state;

FIG. 2 is a bottom front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top front perspective view of the toilet seat of FIG. 1 and the pair of clamps in a retracted state;

FIG. 10 is a bottom front perspective view of the toilet seat of FIG. 1 and the pair of clamps in a retracted state;

FIG. 11 is a top front perspective view of a toilet seat according to another embodiment;

FIG. 12 is a bottom perspective view of the toilet seat of FIG. 11;

FIG. 13 is a front elevation view of the toilet seat of FIG. 11;

FIG. 14 is a rear elevation view of the toilet seat of FIG. 11;

FIG. 15 is a left side elevation view of the toilet seat of FIG. 11;

FIG. 16 is a right side elevation view of the toilet seat of FIG. 11;

FIG. 17 is a top plan view of the toilet seat of FIG. 11; and,

FIG. 18 is a bottom plan view of the toilet seat of FIG. 11. The broken lines in the drawings illustrate portions of the toilet seat, which form no part of the claimed design.

1 Claim, 18 Drawing Sheets
